UNITED STATES PATENT OFFICE.

SEYMOUR M. BRADLEY, OF NEW HAVEN, CONNECTICUT, ASSIGNOR TO THE ENGLISH
& MERSICK CO., OF NEW HAVEN, CONNECTICUT, A CORPORATION.

LATCH FOR VEHICLE DOORS.

Application filed May 17, 1921. Serial No. 470,292.

To all whom it may concern:

Be it known that I, SEYMOUR M. BRADLEY, a citizen of the United States, residing at New Haven, in the county of New Haven 5 and State of Connecticut, have invented a new and useful Improvement in Latches for Vehicle Doors; and I do hereby declare the following, when taken in connection with the accompanying drawings and the characters of reference marked thereon, to be a full, clear, and exact description of the same, and which said drawings constitute part of this application, and represent, in—

Fig. 1 a top or plan view of a latch for 15 vehicle doors constructed in accordance with my invention.

Fig. 2 an inside face view of the same, showing the locking-dog in its raised position.

Fig. 3 a similar view, showing the dog in 20 its locked position in full lines and in its unlocked position in broken lines.

Fig. 4 an inside face view, partly in section, of a modified form of latch embodying 25 my invention.

This invention relates to improvement in latches for vehicle doors, and particularly to latches in which the latch-bolt is adapted to be operated from the inside of the door 30 by a swinging lever or by a rotatable lever, and from the outside of the door by means of a suitable handle operating a roll-back having a cam for retiring the latch-bolt, and particularly to latches in which means are 35 provided for engaging with the cam on the roll-back to prevent the operation of the latch-bolt by the outside handle. Heretofore, a pivotal dog has been employed for the purpose of blocking the movement of the 40 cam on the roll-back, and a separate handle has been provided for operating the dog. The object of this invention is to directly operate the dog by the movement of the latch-bolt lever, and the invention consists 45 in the construction and arrangement of parts as hereinafter described and particularly recited in the claims.

In carrying out my invention, I employ the usual latch case plate 5, sliding latch bolt 50 6 provided with an arm 7 for engagement by a cam 8 on a roll-back 9 adapted to be operated from a suitable handle outside the door. As shown in Figs. 1, 2 and 3 of the drawings, the latch-bolt 6 is operated by a 55 swinging lever 10, all of usual construction.

In the path of the cam 8 I mount a pivotal dog 11, and pivoted to the lever 10 is a slide 12 having a slot 13 through which a stud 14, mounted at the top of the dog, extends, the length of the slot being such that when the handle lever 10 is moved forward, as shown in broken lines, Fig. 2, the dog may be turned down into the path of and against the cam 8 as shown in full lines in Fig. 3 of the drawings, so that the cam 8 is locked 60 against movement and prevents the door being opened from the outside. The dog 11, which is held in position by a spring-latch 15, is adapted to be raised by vertically-movable slide 16 adapted to be engaged by a 65 roll-back 17 of a cylinder-lock mechanism not shown, the arrangement of the dog and mechanism for raising it by a key being the same as that shown and described in application filed November 29, 1920, Serial Number 76 427,122. The dog may thus be lifted out of its locking position from the outside by a suitable key, so that the door may then be opened by the usual outside handle. If the handle-lever 10 be operated from the inside, 70 and moved backward to retire the latch-bolt 6, the first movement of the handle will draw the slide 12 rearward and lift the locking-dog out of its locked position, as shown by 75 broken lines in Fig. 3.

Instead of operating the dog through the medium of a swinging lever, I may employ a construction like that shown and described in an application filed by Kaimer and Ritter in even date herewith, in which, as shown in 80 Fig. 4, the latch-bolt is adapted to be retired by means of a roll-back 18 and by a cam 19 at the lower end of a vertically-arranged rotatable lever 20. The roll-back 18 is formed with a stop-lug 21 arranged to be engaged 85 by vertically-movable dog or bolt 22 extending downward through a suitable housing 23 from an arm 24, which is mounted on the lever 20, the arm being formed with a cam 25 engaged by a pin 26 mounted in the lever, 90 so that, when the lever is turned, the cam 25 will ride over the pin 26 and rest on the arm 24, so as to lift the dog 22 out of engagement with the stop-lug 21. Around the lever 20 and resting upon the arm 24 is a sleeve 27, 95 and this sleeve is coupled by a transverse pin 28 with a push-rod 29 having a push-button 30, which extends upward through a handle lever 31, which is coupled with the spindle 20 and by which the spindle may be 100 110

turned. In this construction, also, the dog or bolt is lifted out of engagement with the cam on the roll-back by the movement of the latch-bolt lever.

5 In either construction it will be noted that means for lifting the dog out of engagement with the cam is directly operated by the latch-bolt lever.

I claim:

10 1. In a latch for vehicle doors, the combination with a latch-bolt, an upwardly-projecting lever-handle inside the door for moving the said bolt, a roll-back adapted to be operated from the outside of the door, independent of the said lever, and adapted to retire the said latch-bolt, a dog adapted to engage directly with said roll-back, and means directly operated by the lever-handle for moving the said dog into and out of the path of the said roll-back.

15 2. In a latch for vehicle doors, the combination with a latch-bolt, of a lever for operating the same, a roll-back by which the latch-bolt may be moved, a dog adapted to be turned into the path of said roll-back, key-operating means for lifting said dog, and connection between the said dog and bolt-lever, whereby the dog may be moved into or out of its locking position by the movement of the said lever.

3. In a latch for vehicle doors, the combination with a latch-bolt and a sliding handle lever adapted to move said latch-bolt, a roll-back by which the latch-bolt may be moved from the outside of the door, a pivotal dog arranged in line with the movement of said roll-back, and connections between the dog and latch-bolt lever whereby the dog may be moved into or out of its locked position by the movement of the said latch-bolt lever.

4. In a latch for vehicle doors, the combination with a latch-bolt and a swinging lever adapted to retire said latch-bolt, a roll-back by which the latch-bolt may be moved from the outside of the door, a pivotal dog mounted in line with said roll-back, and a slide pivoted to the latch-bolt lever and having slot and pin connection with said dog, whereby said dog may be moved into or out of its locked position by the movement of the latch-bolt lever.

In testimony whereof, I have signed this specification in the presence of two subscribing witnesses.

SEYMOUR M. BRADLEY.

Witnesses:

MARTHA M. THEISS,
RUTH E. BRADLEY.
